Assistant Examiner — Rani J Abdallah(74) *Attorney, Agent, or Firm* — Rivka Friedman(57) **CLAIM**

The ornamental design for a bottle, as shown and described.

DESCRIPTION

FIG. 1.1 is a top view of a bottle showing our design;

FIG. 1.2 is a right view thereof;

FIG. 1.3 is a left view thereof;

FIG. 1.4 is a front view thereof;

FIG. 1.5 is a back view thereof; and

FIG. 1.6 is a top perspective view thereof.

The broken lines shown illustrate portions of the bottle, which form no part of the claimed design.

1 Claim, 6 Drawing Sheets(56)
